The ornamental design for a finger protector, as shown and described.

DESCRIPTION

FIG. 1 is a perspective view of the bottom, front and right side of the finger protector embodying my design;

FIG. 2 is a top plan view of the finger protector of FIG. 1; FIG. 3 is a rear elevational view of the finger protector of FIG. 1; and,

FIG. 4 is a left side elevational view of the finger protector of FIG. 1, the right side being a mirror image thereof.

FIG. 5 is a perspective view of the bottom, front and right side of a second embodiment of the finger protector embodying my design;

FIG. 6 is a top plan view of the finger protector of FIG. 5; FIG. 7 is a left side elevational view of the finger protector of FIG. 5, the right side being a mirror image thereof; and, FIG. 8 is a rear elevational view of the finger protector of FIG. 5.
